TREATING ARTIFICIAL FILAMENTS

Hendrik Gerardus van der Waals and George Ephraim Jacob Wiessing, Arnhem, Netherlands, assignors, by mesne assignments, to American Enka Corporation, Wilmington, Del., a corporation of Delaware

Application March 16, 1933, Serial No. 661,084
In Germany March 21, 1932

2 Claims.

(Cl. 18—8)

This invention relates to filaments, particularly of artificial material such as artificial silk. The invention further relates to the production of a body of artificial filaments embodying improvements over those heretofore known.

In the practice heretofore it has been customary to produce bodies of artificial filaments in the form of a ring of circular cross-sections. The freshly spun filaments were formed into the circular body and then permitted to dry. In the drying process there was a shrinking which caused pressure on the various windings because of the resistance of the inner windings to the pressure created by the greater shrinkage of the outer windings. The present invention is intended to obviate the disadvantages of the prior art and to provide an apparatus and a process whereby a new and improved form of body is produced having advantages not inherent in the old forms.

In producing this invention we provide a spinning pot, the inner surface of which is non-circular. Preferably the inner surface has one or more inwardly projecting portions which may be of greater or lesser extent. The freshly formed artificial filaments are spun against this surface and the body so formed is removed.

Upon shrinkage of the outer layers the pressure caused thereby is taken up by reason of the fact that the body has an outline which is non-circular so that the pressure tends to cause the body to assume a circular shape and thus minimize or even eliminate the pressure due to shrinkage. There may be both a yielding of the inner windings by reason of the irregular form thereof, or an equalization of the pressure of the several layers by the compensated shrinkage of the inwardly projecting portions of the body.

In the accompanying drawing constituting a part hereof and in which like reference characters indicate like parts;

Figure 1 is an end view of one form of a spinning pot made in accordance with this invention and adapted for use to produce the desired form of body of artificial filaments;

Figures 2, 3, 4, 5 and 6 are similar views of modified forms of spinning pots illustrating some of the many forms which the apparatus may assume in accordance with this invention, and

Figures 7 and 8 are end views of two forms of bodies of artificial filaments adapted to be produced by the present invention.

The spinning apparatus consists essentially of pot 1 from the inner surface of which projections 2 face inwardly. In Figure 1 there is provided a pot 1 into which is fitted a ring 6 having in-

tegrally formed therewith projecting portions 7 facing inwardly. In Figure 2 there is illustrated a device similar to Figure 1 with the difference that instead of integrally formed projecting portions there are provided portions 8 held to the ring 6 by screws 9.

In Figure 3 there is provided a pot 1 and separate and distinct therefrom is a corrugated member 10 of any suitable material such as metal, molded rubber or the like. Preferably the member 10 is elastic so that it can be readily inserted into and removed from the pot 1.

In Figure 4 is shown a similar arrangement wherein instead of a single corrugated member 10 there are provided two such members 11 and 12 which when fitted together within the pot 1 touch each other at points 13 and 14. Figure 5 shows a similar arrangement in which there are members 15 and 16 secured together at point 17 by a hinge in order that when removed from pot 1, the members 15 and 16 may be opened and the body of filaments more readily removed. Figure 6 shows a similar device in which the member 18 is of molded material such as rubber, and preferably molded in a relatively flat position and split at point 19. The member 18 has a tendency to flatten out when removed from pot 1 and thus to readily release the body of filaments.

In use we may set the spinning pot in a suitable apparatus and cause the filaments to be spun against the interior surface thereof by centrifugal force to form a body such as shown in Figures 7 and 8. The body is removed from the spinning pot in any well known manner. In Figure 7 the body 20 is shown as having a plurality of outwardly extending projections 21 and corresponding projections 22 on the inner surface thereof. In Figure 8 the body 20 has similar projections 21, but of lesser prominence than in Figure 7 and the inner surface 23 is substantially circular. By reason of the shape when a body of freshly spun filaments shrinks, the shrinkage of portions 21 will cause a yielding of portions 22 and thus avoid excess pressure on the body as a whole. The shrinkage of portions 21 will be partially compensated for by the shrinkage in the reverse direction of the inwardly extending portions 24 between portions 21.

Although we have described our invention setting forth various embodiments thereof, the invention is not to be limited by the specific examples, as said examples merely illustrate the many forms of the present invention. Spinning pots may be made of various metals, such as alumi-

num, nickel, steels, rubber, artificial resins, Celluloid and the like. It is desirable that the surfaces coming in contact with the artificial filaments be of acid proof material and for this purpose various metals which are not acid proof may be furnished with a protective coating. In some cases where a solid member is used for the spinning pot as in Figures 1 and 2, a lining of soft rubber may be provided in order to firmly hold the body of filaments together when removed from the pot and at the same time allowing ready removal of the pot from the lining. The number of projections may be made greater or smaller and they may be of greater or lesser prominence. These and other changes may be made in our invention the scope of which is set forth in the claims appended hereto.

What we claim is:

1. An apparatus for collecting artificial silk comprising in combination a spinning pot which is circular in cross-section and a member of generally similar cross-section located within the pot and being of substantially the same height as the inner wall thereof but unattached to said inner wall, the member being provided with recesses in its outer wall to form spaces between the inner wall of the pot and the corrugated member to facilitate simultaneously removal of the member with a thread package formed

therein and having inwardly projecting portions of such conformation as to produce a corrugated, endless inner embracing wall, thereby causing said member to form corrugations of sufficient size and shape to introduce slack throughout all parts of the thread package wherein resistance to contraction would otherwise occur whereby when the package is formed and dried, uniform shrinkage is produced.

2. An apparatus for collecting artificial silk comprising in combination a spinning pot which is circular in cross-section and a resilient member of generally similar cross-section located therein and being separable at at least one point which provides ends abutting each other, said member being unattached to the inner wall of the pot and readily removable therefrom and being of substantially the same height as said inner wall, the said member having inwardly projecting portions of such conformation as to produce a corrugated, endless inner embracing wall surface to form corrugations of sufficient size and shape to introduce slack throughout all parts of the thread package wherein resistance to contraction would otherwise occur whereby when the package is formed and dried, uniform shrinkage is produced.

HENDRIK GERARDUS VAN DER WAALS.
